COMBINATION RETORT AND HEARTH FOR STOKERS

Original Filed June 19, 1940

Fig. 2.

UNITED STATES PATENT OFFICE

2,392,460

COMBINATION RETORT AND HEARTH FOR
STOKERS

Thomas C. Cheasley, Kansas City, Mo.

Original application June 19, 1940, Serial No.
341,272. Divided and this application January
16, 1943, Serial No. 472,580

8 Claims. (Cl. 122—374)

This invention relates to a combination retort and hearth particularly adapted for use in stoker fed boilers and is a division of my copending application filed June 19, 1940, Serial No. 341,272, now Patent Number 2,320,410.

Boilers are usually constructed with water legs forming side walls of the fire-box. Consequently dirt, scale and foreign matter in the boiler water settle to the bottom of the water legs and collect upon the mud rings so that circulation in that portion of the water legs is substantially blocked by the settled material. When such boilers are equipped for stoker feed of the fuel the hearth of the stoker mechanism is located adjacent the mud ring portion of the water legs, consequently the intense heat of the fuel plays directly thereon with the result that the inner walls of the water legs are excessively heated and are apt to give way under boiler pressure.

It is, therefore, a principal object of the present invention to provide means in association with the hearth of a stoker mechanism for protecting the lower portion of the water legs from direct contact with the inner walls thereof and thereby prevent overheating thereof.

Other objects of the invention are to provide the hearth of the stoker mechanism with a water-cooled curb to form a protection for mud ring portions of the water legs; and to provide means for effecting circulation of a cooling liquid through the hearth and particularly the portion thereof forming the curb thereof.

It is a further object of the invention to provide a boiler with means in association with the water-cooled hearth and retort to effect positive circulation at the mud ring portions of the water legs of the boiler.

In accomplishing these and other objects of the invention, I have provided improved structure, the preferred forms of which are illustrated in the accompanying drawing, wherein:

Fig. 1 is a vertical section through the lower portion of the fire-box of a boiler equipped with a stoker apparatus and hearth embodying the features of the present invention.

Fig. 2 is a modified form of the invention showing the water legs provided with extensions which cooperate with water jacket extensions of a retort for forming a water-cooled hearth through which water from the lower portions of the water legs is circulated to control temperature of the hearth and prevent over-heating of the lower portions of the fire-box walls.

Referring more in detail to the drawing:

1 designates an ordinary fire tube boiler having

a fire-box 2, the walls of which comprise inner and outer sheets 3 and 4 spaced apart to provide water legs 5 for the circulation of boiler water around the fire-box, the lower edges of the sheets 5 being connected to form a mud ring 6 that is supported upon the boiler foundation 7 which forms the walls of an ash-pit 8.

The front of the fire-box is provided with the usual door opening 9 opening into the fire-box.

Extending through the front of the foundation 10 are air and fuel ducts 10 and 11 of a stoker apparatus which ducts are connected with a feed hopper and fan (not shown). The air duct 10 discharges directly into the ash-pit and supplies combustion supporting air for the fuel delivered through the duct 11. The duct 11 projects into the ash-pit and terminates in an upwardly directed outlet 12 forming the lower section of a retort and having a flange 13 for seating the upper section 14. The upper portion of the outlet 12 cooperates with the upwardly diverging wall 15 of the retort to provide a substantially conical shaped retort chamber 16. The wall 15 terminates near the horizontal plane of the mud ring 6 in a laterally extending plate portion 17 which forms the fuel supporting portion of a hearth.

In the illustrated instance, the outer marginal portion of the plate 17 terminates short of the water legs of the fire-box and connected therewith is an upwardly extending curbing flange 19 curving into an outwardly directed rim portion 20 which substantially closes the space around the hearth and prevents burning fuel and ashes carried on the plate 17 from contacting the inner surfaces of the water legs of the boiler, the flange 19 being of sufficient height to extend upwardly of the water leg so that it is above that portion of the water leg in which the mud and sediment usually collect.

Mounted upon the plate portion 17 and arranged circumferentially of the retort chamber 16 is a tuyère 21. The tuyère includes a ring having an inner wall portion 22 provided with a plurality of air discharge openings 23. The upper part of the wall 22 rounds outwardly and downwardly, as at 24, and connects with an outer wall portion 25 provided at its base with a laterally extending flange 26 seated upon the plate portion 16 of the hearth. The tuyère thus forms an annular manifold chamber 27 having connection with the ash-pit 8, later described. The wall portion 25 of the tuyère may also have a series of air discharge openings 28 which are directed toward the fuel bed which is supported upon the plate 17.

Fuel is delivered from the hopper (not shown) of the stoker through the duct 11 by a screw conveyor 29 to maintain the retort chamber full of fuel with the fire bed above the tuyère when the stoker is in operation.

Gas evolved from the fuel in the retort incidental to heat of the burning fuel passes upwardly into contact with the air admitted through the openings 23 and 28 of the tuyère so as to maintain the coking fuel in burning condition with the hottest part of the fire extending uniformly over the top of the tuyère. The ash gravitates downwardly over the rounding portion 24 and accumulates upon the plate 17. When the rate of feed of fuel and amount of air delivered are in proper proportions using a good grade of stoker coal, the fire may be satisfactorily maintained but any stoppage of the fuel feed or with too large amount of air, the fire may burn down into the retort and below the level at which the air enters through the tuyère with the result that the metal wall of the tuyère is excessively heated and soon deteriorates. With certain types of coal, the fuel cakes into a solid mass which arches over the tuyère so that the fire cannot pass therethrough with the result that the fire burns on the bottom side and around the edges and into the retort, causing damage to the retort. Another disadvantage is that the hearth becomes excessively hot and causes the clinker ash of the so-called fusion coals to adhere thereto and make it difficult to remove.

To overcome these and other difficulties of present stoker mechanisms, I provide the retort with a water jacket 30 through which water is circulated to maintain a predetermined maximum temperature of the retort and prevent injury thereto in case the fire should burn therein. I have further provided the plate 17 and the curbing 19 which protect the mud ring portion of the water legs with water jackets 31 and 32 which may be formed as continuations of the water jacket 30, thereby preventing the plate 17 and curbing 19 from heating to the point where the clinker will tend to stick thereto. Cooling of the retort has the advantage in maintaining the fire at a higher level and by directing the combustion supporting air through the fuel bed above the water-cooled section the fuel bed level is kept out of the retort chamber.

In the form of the invention illustrated in Fig. 1, the lower portion of the upper section 14 of the retort has a laterally extending peripheral portion 30 connecting with an outer wall portion 34 extending substantially parallel with the retort wall 15 to form a water passageway 35 therebetween. The upper portion of the wall 34 curves outwardly in downwardly spaced relation with the plate 17, as at 36, into a substantially horizontal plate portion 37 so as to form a water circulating space 38 under the plate 17 and which has connection with the water circulating space 35.

The plate portion 37 terminates adjacent the inner faces of the fire legs, as at 39, and connects with the rim 20 by a wall 40 to form a water circulating space 41 surrounding the curbing 19, which space is connected with the circulating space 38. Water is admitted to the lower portion of the circulating space 36 through an inlet pipe 42 and is discharged through an outlet pipe 43 which is shown as connected with the water circulating space 35.

In order to admit air from the ash-pit to the manifold chamber of the tuyère, the upper and

lower plate portions 17 and 33 are connected by tubular ducts 44 so that the combustion supporting air is conveyed through the water space and preheated by the water circulating through the respective passageways. If it is desired to provide a live plate for the hearth, the plate portions 17 and 37 are connected by tubular ducts 45 so that air is admitted into the fuel bed supported by the hearth.

10 In order to provide a seal between the water legs and wall 40, the wall 40 is slightly spaced from the inner plates 3 of the water legs to accommodate a sealing material 46 that is inserted therein.

15 With the structure thus described, the wall 15 of the retort is kept in cool condition and no air is admitted thereto so that the fire is maintained above the dead plate and in position to heat the water legs of the boiler. However, the 20 water-cooled curbing portions of the hearth prevent overheating of the mud ring portions of the water legs.

Gases from the fuel are evolved in the retort and mixed with the combustion supporting air 25 admitted to the tuyère through the tubular ducts 44 which air has been heated by the water circulated through the water jacket. The coal cokes in the upper portion of the retort and is displaced 30 therefrom by the continued inlet of additional coal by the screw conveyor so as to maintain the fuel bed. The ashes from the fuel bed fall over the rounded portion of the tuyère and form a clinker which collects upon the relatively cool surfaces of the hearth. The ash is therefore 35 readily disposed of in the form of clinkers.

In the form of the invention shown in Fig. 2, the water jacket 41 of the retort terminates adjacent the flange 48 of the tuyère 49 and abuts inwardly extending horizontal extensions 50 of the water legs 51 of the boiler, the extensions 40 cooperating with the retort to form a fuel supporting hearth 52 cooled by water circulated in the legs of the boiler. The extensions 50 are connected with the water-cooled space of the 45 retort by pipes 53. Thus the boiler water tends to circulate in the lower portion of the water legs to prevent settling of mud and the like on the mud ring of the boiler. With this arrangement the curbing of the hearth may be omitted 50 since the inner wall of the fire-box does not overheat because foreign materials do not settle out in the water legs of the boiler.

From the foregoing it is obvious that I have provided protection of the retort of the stoker apparatus so as to avoid overheating thereof, thereby providing a retort of longer life and more efficient operation. It is also obvious that I have provided a water-cooled hearth which is equipped with a water-cooled curbing to prevent overheating of the inner walls of the water legs of a boiler. Consequently the temperatures of the hearth are controlled so as to avoid sticking of clinkers to the legs of the boiler and metal surfaces of the hearth with the result that these 65 clinkers may be readily removed. While it is desirable to provide a continuous flow of water through the cooling jackets there is no loss of efficiency or increase in expense of operation as the heated water may be used in the boiler for increasing circulation therein.

What I claim and desire to secure by Letters Patent is:

1. In combination with the fire-box of a boiler having walls thereof formed by spaced inner and outer sheets connected at their lower edges to

form water legs, a stoker mechanism for supplying fuel to the fire-box including a hearth adapted to support burning fuel, and a water-cooled curbing surrounding the hearth projecting upwardly alongside inner faces of said inner sheets for preventing overheating of the inner sheets of the fire-box adjacent said hearth.

2. In combination with the fire-box of a boiler having water legs, a retort supported in the fire-box, and a jacket surrounding the retort and forming a space for circulation of a cooling medium, said water jacket including an upwardly extending curbing portion lapping the water legs for protecting the legs of the boiler from direct heat resulting from combustion of fuel delivered through said retort.

3. A mechanism of the character described including, a retort, a hearth for receiving fuel thereon from the retort, a water jacket underlying the hearth, a tuyère encircling the retort, and a curbing for the hearth having a passageway connected with said water jacket, said curbing having a height substantially corresponding to height of the tuyère.

4. In combination with a fire box of a boiler having water legs, a retort supported in the fire box, a hearth for receiving fuel thereon from the retort, a water jacket underlying the hearth, a tuyère encircling the retort and extending above the hearth, and a curbing for the hearth extending upwardly of the water legs substantially the height of the tuyère and having a passageway connected with the water jacket.

5. A combination retort and hearth for a fire-box having water legs forming the side walls of said fire-box including a retort, including a hearth for receiving fuel from the retort, and a

curbing extending around the hearth and overlapping portions of the water legs adjacent the hearth, said curbing having a water passageway therethrough.

6. A combination retort and hearth for a fire-box having water legs forming the side walls of said fire-box including a retort, including a hearth for receiving fuel from the retort, a water jacket underlying the hearth, and a curbing extending around the hearth and overlapping portions of the water legs adjacent the hearth, said curbing having a passageway connected with the water jacket.

7. A combination retort and hearth for a fire-box having water legs forming the side walls of said fire-box including a retort, including a hearth for receiving fuel from the retort, a water jacket underlying the hearth and surrounding the retort, and a curbing extending around the hearth and overlapping portions of the water legs adjacent the hearth, said curbing having a water passageway and connected with the water jacket.

8. In combination with a fire-box of a boiler having walls thereof formed by spaced inner and outer sheets to provide water legs and a mud ring connecting said inner and outer sheets, a stoker mechanism for supplying fuel to the fire-box including a retort, a hearth surrounding the retort, means cooperating with the hearth and said retort to provide a passageway for circulation of water, a tuyère surrounding the retort and extending above the hearth, water circulating means surrounding the hearth and located within the fire-box for providing water circulation in cooling relation with the portion of the inner sheets above the mud ring.

THOMAS C. CHEASLEY.
